UNITED STATES PATENT OFFICE

JAMES S. ATTERBURY AND THOMAS B. ATTERBURY, OF BIRMINGHAM, PENN.

DESIGN FOR GLASSWARE.

Specification forming part of Design No. 5,900, dated June 4, 1872.

SPECIFICATION.

To all whom it may concern:

Be it known that we, JAMES S. ATTERBURY and THOMAS B. ATTERBURY, of Birmingham, in the county of Allegheny and State of Pennsylvania, have invented a new and useful Design for Glassware; and we do hereby declare the following to be a full, clear, and exact description thereof, reference being had to the accompanying drawing making a part of this specification, in which—

Figure 1 is a plan view of a dish showing our improved design, and Fig. 2 is a longitudinal section through $x x$, Fig. 1.

To enable others skilled in the art to make and use our improved design, we will describe the same.

It consists of a representation of a fish, having the substantial features of ornamentation shown and described, worked or impressed onto a pickle-dish or other dish-shaped article of glassware.

The dish shown is made in any way known in the art.

The body of the dish, which is finished in imitation of scales a , represents the body A of the fish. The ends B and C represent, respectively, the head and tail of the fish. $D D$ represent the gills. The body of the dish, in which is represented the body A of the fish, is concave or dish-shaped.

It does not matter which variety of fish is represented, provided it be one presenting a substantially like ornamentation to that shown.

What we claim as our invention, and desire to secure by Letters Patent, is—

The design for ornamentation of glass dishes, substantially as shown and described.

In testimony whereof we, the said JAMES S. ATTERBURY and THOMAS B. ATTERBURY, have hereunto set our hands.

JAS. S. ATTERBURY.
THOS. B. ATTERBURY.

Witnesses:

E. G. KEEHAN,
TOM C. CLARK.
